H. H. HEWITT.

CAR TRUCK.

APPLICATION FILED DEC. 8, 1911.

1,072,722.

Patented Sept. 9, 1913.

UNITED STATES PATENT OFFICE

HERBERT H. HEWITT, OF BUFFALO, NEW YORK.

CAR-TRUCK.

1,072,722.

Specification of Letters Patent.

Patented Sept. 9, 1913.

Application filed December 8, 1911. Serial No. 664,634.

To all whom it may concern:

Be it known that I, HERBERT H. HEWITT, a citizen of the United States, residing at Buffalo, in the county of Erie, State of New York, have invented certain new and useful Improvements in Car-Trucks, of which I do declare the following to be a full, clear, and exact description, reference being had to the accompanying drawing, forming part of 10 this specification.

The present invention seeks to improve the construction of car truck and the manner in which the journal boxes of the wheel axle are connected to the side frames of the trucks 15 and in which construction the boxes are free to rock in vertical transverse planes, thereby avoiding any straining or distorting of the parts incident to irregularities of the track and compensating for any distortion of the 20 truck frame in adjusting itself to the inequalities of the track.

The invention consists in the novel features of construction hereinafter described, 25 illustrated in the accompanying drawing and particularly pointed out in the claims at the end of this specification.

Figure 1 is a plan view showing one half of a car truck having my invention applied thereto, parts being shown in horizontal section. Fig. 2 is a view in end elevation, parts being shown in vertical section. Fig. 3 is a view in vertical cross-section on line 3—3 of Fig. 2. Fig. 4 is a view in vertical transverse section on line 4—4 of Fig. 2.

35 In the accompanying drawing, I have illustrated one half only of a car truck having my invention applied thereto. But it will be understood that the other half of the truck will correspond in construction to that 40 shown in the drawing. The improved side frame A of my truck is shown as formed of a single casting, and the side frames at opposite sides of the truck will be connected together by suitable transverse members.

45 Preferably, the side frames of the truck will be connected, as shown in the drawing, by means of a transverse member or transom B in such manner that the side frames may rock in vertical planes with respect to said transom. An example of this type of connection between the side frames and the transverse member or transom of the truck is shown in Letters Patent No. 1,009,747, granted to me November 28, 1911. To this 50 end, the side frame A is shown as formed

with a large circular opening having inner and outer flanges 2 and 3 within which is journaled the hollow, circular end 4 of the transom B. In order to retain the side frame A in secure position upon the end 4 of the transom, the side frame A is shown as formed with pockets 5 adapted to receive suitable keys C that may be conveniently held in place within the pockets 5 by the pins 6. The ends of the keys C project 60 through segmental slots 7 that are formed in the wall of the circular end 4 of the transom B, the slots 7 being somewhat larger than the keys C so as to permit the slight rocking movement of the side frame with respect to 65 the transom. A truck bolster D is shown as mounted above the transom B and supported upon springs E, but these features are not essential to the present invention. In assembling the parts the side frame A will be 70 slipped over the circular end 4 of the transom B and the keys C will then be placed within the pockets 5 of the side frame and will be retained in such pockets by the pins 6, as clearly shown in Figs. 1 and 2 of the 75 drawing.

The journal boxes E that receive the journals f of the car axles F may have a construction similar, in the main, to that prescribed by the Master Car Builder's Association, the journal boxes E being provided at their outer ends with suitable lids e and being provided upon their interior with suitable brasses G for the journals f of the car axles. Inasmuch, however, as my improved 85 construction of truck provides for a transverse rocking of the journal box with respect to the side frame, the journal brass G may rest directly against the under side of the top of the box E and the use of keys or 90 wedges between these parts may therefore be 95 dispensed with.

The preferred manner of connecting the journal boxes E to the side frame A will 100 next be described, although I wish it distinctly understood that the pivotal connection of the journal boxes to the side frame in manner permitting the boxes to rock at right angles to the side frame may be accomplished in various other ways without departing from the scope of the invention. A 105 stud or journal H extending lengthwise of the side frame is the preferred means for pivotally connecting each of the journal boxes E with the side frame and, prefer- 110

ably, each of the journal boxes E has a stud or journal H formed integral with one of its side walls. Each of the studs or journals H is revolubly mounted within a circular bearing 8 at the end of the side frame A, and the stud or journal H is held in place with respect to the bearing 8 by a suitable key 9, or in any other convenient manner. In order to give greater strength and rigidity of connection between the journal boxes E and the side frame, I prefer to form the studs or journal H of considerable length and to provide the side frame A with supplemental inner bearings 10 adapted to receive the circular inner end portions h of the studs or journals H.

From the foregoing description it will be seen that when the parts are assembled, as shown in the drawing, the journal boxes E will be free to rock or swivel in a vertical plane at right angles to the vertical plane of the side frame of the truck. Under this arrangement the journal boxes can adjust themselves to the position of the side frame and also to the axles or journals on which it is mounted, thus providing for a perfect alinement of the journal bearings on the journals no matter how badly distorted the truck frame may be in adjusting itself to the inequalities or irregularities of the track. This manner of connecting the journal boxes to the side frame will be found advantageous, whether the side frame be pivotally united to the truck transom or not, since whatever be the means of connecting the side frames of a car truck together, there is inevitably more or less distortion of the parts incident to irregularities or inequalities of the track. By providing the journal boxes with long, laterally projecting studs or journals and by providing the side frame with supplemental inner bearings for the inner ends of said studs or journals, a much more perfect alinement of the circular or bearing portions h and h' of the studs or journals H in the journal bearings of the side frame is insured, thereby preventing any uneven wear or any tendency to distort the side frame. One advantage incident to forming the side frame with open bearings at its ends to receive the studs or journals that project laterally from the axle boxes E, is that it can be readily detached from the side frames whenever it becomes necessary to change the wheels and axles, and this, too, without removing the truck from beneath the car.

In the preferred form of my invention, each side frame comprises an integral casting having an enlarged central portion and upper and lower inclined, converging arms or portions which extend from the enlarged central portion on opposite sides of openings a' and which are united at the ends of the side frame by the integral bearings 8.

These parts are preferably formed of an integral casting, as stated, and comprise a central web having marginal strengthening flanges a. This construction insures the greatest possible strength with the least weight and is well adapted to support the swiveled journal boxes at the ends of the side frame to resist the strains to which the frame and boxes are subjected. Inasmuch as the bearings of the side frame that receive the studs or journals of the boxes are formed upon the longitudinal central line of the side frame and between the inner and outer faces thereof, the side frames are reversible and interchangeable. The improved truck is strong and rigid in construction and at the same time the journal boxes are free to rock in transverse planes without distorting or straining the parts. Furthermore, the side frames, in the preferred form of the invention can swing in vertical longitudinal planes, so that the wheel axles are free to rock transversely and the wheels of the truck can, at all times, rest solidly upon the track, in spite of irregularities thereof. The journal boxes, while free to rock in transverse planes, are securely held against relative vertical movement upon the ends of the side frames, but in such a manner that they can be withdrawn from the side frames in longitudinal and horizontal direction, so that they can be readily detached, as stated, for repairs or the like.

By my present invention I am enabled to use axle boxes that follow, in the main, the construction prescribed by the Master Car Builder's Association, while at the same time providing for such swiveling movement of the boxes as will insure a perfect adjustment of the parts of the truck when distorted or riding over uneven surfaces.

I wish it distinctly understood that while I have described what I regard as the preferred embodiment of my invention, the details of construction above set out may be varied within wide limits without departing from the scope of the invention and features of the invention may be employed without its adoption as an entirety.

Having thus described my invention what I claim as new and desire to secure by Letters Patent, is:

1. In a car truck, the combination of parallel side frames, a transverse connecting member whereon said side frames are centrally mounted to rock independently in vertical planes, journal boxes at the ends of said side frames, and studs or journals at the sides of said journal boxes for connecting the same to said side frames in manner permitting the free rocking movement of said journal boxes in transverse vertical planes at right angles to said side frames.
2. In a car truck the combination of a side frame, and journal boxes at the ends of

5 said side frame, the inner sides of said journal boxes being pivoted to the outer ends of said side frame in manner permitting said boxes to rock at right angles to said frame.

10 6. In a car truck, the combination with a side frame, journal boxes at the ends of said side frame, studs or journals fixed to said journal boxes and projecting inwardly toward the center of the side frame and bearings at the ends of the side frame wherein said studs or journals are mounted in manner permitting said boxes to rock in vertical planes and transversely of the side frame.

15 7. In a car truck, the combination of a side frame, journal boxes for receiving the car axles and studs or journals projecting from said journal boxes lengthwise of the side frame and serving to connect said boxes 20 to the side frame and to hold the same against relative vertical movement while permitting the boxes to rock at right angles to said frame.

25 8. In a car truck, the combination of parallel side frames, a transverse connecting member having means for supporting the car body, said side frames being centrally journaled on the ends of said transverse connecting member to rock in parallel vertical planes, journal boxes at the ends of said side frames, pivotal connections between the sides of said journal boxes and said side frames permitting the free transverse rocking movement of said journal boxes in vertical planes at right angles to said side frames, said journal boxes being held against rocking movement in the planes of said side frames.

30 9. In a car truck, the combination of a side frame, and journal boxes having integral studs on their sides extending lengthwise of the side frame, said side frame having bearings at its ends for receiving said studs or journals, said studs or journals and 45 said bearings being arranged to hold said journal boxes against relative vertical movement upon the ends of said side frames while permitting the rocking movement of said journal boxes in transverse vertical planes.

35 10. In a car truck, the combination of a side frame having journal bearings at its ends, journal boxes at the ends of said side frame and studs or journals projecting inwardly from said journal boxes and pivotally mounted within the bearings at the ends of the side frame in manner permitting the journal boxes to rock at right angles to said side frame, said studs or journals being 40 withdrawable from the bearing of said side frame by movement lengthwise of said frame.

45 11. In a car truck the combination of a side frame having journal bearings at its ends, journal boxes at the ends of said side

frame and studs or journals projecting inwardly from said journal boxes and pivotally mounted within the bearings at the ends of the side frame in manner permitting the journal boxes to rock at right angles to said side frame, said studs or journals being withdrawable from the bearings of said side frame and means for holding said studs or journals within said bearings of the side frame. 75

12. In a car truck, the combination of a side frame having two aligned bearings located at each side of its center and open toward its ends and long studs or journals 80 projecting from the sides of the journal boxes and pivotally mounted in said bearings in manner permitting said boxes to rock at right angles to said frame.

13. A side frame for car trucks provided 85 at its ends with horizontal journal bearings extending lengthwise of said frame and open at the ends of said frame, said bearings being adapted to receive studs or journals projecting from the car journal boxes. 90

14. A car truck comprising a side frame, a transverse member pivotally connected to said side frame to permit the latter to rock in vertical direction at right angles to said transverse member, and journal boxes pivoted to said side frame upon axes extending lengthwise of the latter in manner permitting said boxes to rock at right angles to said frame. 95

15. A car truck comprising a side frame 100 having a central circular opening, a transverse member having a hollow, circular end revolvably mounted within said transverse opening of the side frame and one or more keys for holding said side frame in engagement with said transverse member, said side frame being provided with pockets wherein said keys are fixed and the end of said transverse member being provided with slots into which said keys project. 110

16. In a car truck, parallel side frames, a transverse connecting member provided with supports for the car body, said side frames being centrally connected to the ends of said transverse connecting member in 115 manner permitting the independent rocking movement of said side frames in longitudinal vertical planes, and axle boxes pivotally mounted upon the ends of said side frames in manner permitting the independent rocking movement thereof in transverse vertical planes at right angles to the side frames, said axle boxes being removable from said side frames in longitudinal direction. 120

17. In a car truck, the combination of parallel side frames, a transverse connecting member extending between said side frames and connected thereto in manner permitting said side frames to move independently in 130

vertical planes, journal boxes at the ends of said side frames, and studs or journals having axes extending lengthwise of said side frames and whereby said journal boxes are supported on said side frames in manner permitting the rocking movement thereof in transverse vertical planes at right angles to said side frames.

15. A car truck comprising connected side frames and journal boxes for receiving the axle journals pivotally connected to the ends of said side frames in manner permitting the rocking movement of said journal boxes in transverse vertical planes, said journal boxes being removable in longitudinal direction from the ends of said side frames.

16. A car truck comprising parallel side frames, a transverse member provided with supports for the car body and removably connected at its ends to said side frames in manner permitting the independent movement of said side frames in vertical planes, and journal boxes pivotally mounted on the ends of said side frames to rock in transverse vertical planes, said journal boxes being removable longitudinally from the ends of said side frames, and means for normally holding said journal boxes against such longitudinal movement.

30 17. A car truck comprising connected side frames, journal boxes for receiving the axle journals, and means pivotally connecting said journal boxes to the ends of said side frames comprising studs or journals and coöperating bearings arranged to hold said journal boxes against relative vertical movement upon the ends of said side frames while permitting the rocking movement thereof in transverse vertical planes.

40 18. A car truck comprising connected side frames, journal boxes for receiving the axle journals, and means pivotally connecting said journal boxes to the ends of said side frames comprising studs or journals and coöperating bearings permitting the rocking movement of said journal boxes in transverse vertical planes, said pivotal connecting means being arranged to permit the removal of said journal boxes by movement lengthwise of said side frames.

50 19. A car truck comprising connected side frames, journal boxes for receiving the axle journals, and means pivotally connecting said journal boxes to the ends of said side frames comprising integral journals upon one of said parts and integral bearings upon the other of said parts, said journals and bearings being arranged to hold said journal boxes against relative vertical movement upon the ends of said side frames while permitting the rocking movement thereof in transverse vertical planes.

60 20. A car truck comprising connected side frames, journal boxes for receiving the axle journals, and means pivotally connecting

said journal boxes to the ends of said side frames comprising integral studs upon one of said parts and integral bearings for said studs upon the other of said parts, said studs and bearings being arranged to permit the rocking movement of said journal boxes in transverse vertical planes and the removal of said journal boxes by movement lengthwise of said side frames.

70 21. A car truck comprising parallel side frames, a transverse connecting member extending between said side frames, each of said side frames comprising an enlarged central portion, converging upper and lower side arms extending from said central portion, and bearing portions connecting the outer ends of said side arms, the enlarged central portions of said side frames having openings engaging said transverse connecting member in manner permitting the independent movement of said side frames in vertical planes, and journal boxes pivotally mounted upon the bearing portions of said side frames in manner permitting the rocking movement of said journal boxes in transverse vertical planes.

75 22. A car truck comprising parallel side frames, a transverse connecting member for supporting the car body, each of said side frames comprising an enlarged central portion, integral converging upper and lower side arms extending from said central portion and integral bearing portions connecting the ends of said side arms, the enlarged central portions of said side frames having cylindrical bearing openings for engaging the ends of said transverse connecting member in manner permitting the independent rocking movement of said side frames in vertical planes, and journal boxes having pivotal connections between the bearing portions at the ends of said side frames arranged to hold the bearing boxes against vertical movement while permitting the transverse rocking movement thereof.

80 23. A car truck comprising parallel side frames, a transverse connecting member, said side frames having transverse cylindrical bearings for engaging the ends of said connecting member, journal boxes at the ends of said side frames and pivotal connections between said boxes and said side frames comprising studs or journals on one of said parts and coöperating bearings on the other of said parts, and the axes of said studs or journals being arranged upon a line extending lengthwise of said side frames and through the axes of the central cylindrical bearings thereof.

85 24. A side frame for car trucks comprising an integral casting having a central opening for engaging the ends of a transverse connecting member and a plurality of journal bearings on opposite sides of said central opening having axes extending

lengthwise of the frame and adapted to receive studs or journals projecting laterally from the axle journal boxes.

25. A side frame for car trucks comprising an integral casting provided at its center with a transverse bearing opening adapted to receive the end of the transom and provided at its ends with journal bearings extending lengthwise thereof and adapted to 10 receive studs or journals projecting laterally from the car axle journal boxes.

26. A side frame for car trucks comprising an integral casting having an enlarged central portion, converging upper and lower

side arms extending from said central portion and bearing portions connecting the ends of said side arms, said enlarged central portion having a transverse cylindrical bearing opening adapted to receive the end of the transverse connecting member and said bearing end portions being provided with journal bearings having axes extending lengthwise of said side frame. 15 20
